UNITED STATES PATENT OFFICE.

LAROY S. PFOUTS AND LORENZO D. BALL, OF CANTON, OHIO; SAID PFOUTS
ASSIGNOR TO GEORGE HUMPHRIES.

BOOT OR SHOE SOLE.

SPECIFICATION forming part of Letters Patent No. 498,942, dated June 6, 1893.

Application filed July 22, 1892. Serial No. 440,899. (No model.)

To all whom it may concern.

Be it known that we, LAROY S. PFOUTS and LORENZO D. BALL, citizens of the United States, residing at Canton, in the county of Stark and State of Ohio, have invented certain new and useful Improvements in Boot or Shoe Soles; and we do hereby declare that the following is a full, clear, and exact description of the same, reference being had to the annexed drawings, making a part of this specification, and to the letters of reference marked thereon, in which—

Figure 1, is a view showing the different sections detached. Fig. 2, is a longitudinal section through line $x-x$, Fig. 1. Fig. 3, is a transverse section through line $y-y$, Fig. 1. Fig. 4, is a detached view of one of the heel-plates.

The present invention has relation to boot or shoe soles and it consists in the peculiar construction hereinafter described and particularly pointed out in the claim.

Similar letters of reference indicate corresponding parts in all the figures of the drawings.

In the accompanying drawings, A represents the ends of the sections of the sole proper, and B represents the center sections. The sections A, are each provided with the inclined lugs or studs a , which are substantially of the form shown in the drawings, and as shown the bottom or end faces of said studs are inclined from their heels to their points, and the top or upper sides of said studs are formed straight, and in line with the top or upper faces of the sections A. The center section B, is provided with the inclined notches or recesses b , which notches or recesses are located substantially as illustrated in Fig. 1.

The notches or recesses b , are provided with inclined faces, which inclined faces correspond with the inclination of the studs a , said notches and studs being so arranged that when the edges of the sections A, and B, are brought together as illustrated in Fig. 2, the sections forming the shoe sole proper, will be brought in proper alignment, thereby providing a means for assisting in holding the sections in proper position upon the shoe sole. The stud a , and the recess b , serve also for the purpose of assisting in holding the sections in proper lateral adjustment. It will be

understood that by our peculiar and novel arrangement, of uniting the edges of the sections together, the shoe-sole formed by the sections A, and B, will have a sufficient amount of flexibility to compensate for any bending of the leather sole upon which the sections A, and B, are attached. For the purpose of forming a metal shoe-sole that will be light and at the same time have the desired amount of wearing quality, we prefer to form the sections A, and B, of aluminium. The heel-plate C, may be of the form illustrated in Fig. 4, and is attached to the heel of a boot or shoe in the ordinary manner. For the purpose of providing a metal boot or shoe sole that will not slip, the bottom or under faces of the sections A, and B, are provided with the grooves c , which grooves may be arranged as illustrated in the drawings, or they may extend across the bottom or under faces of the sections in any other direction from the one shown in the drawings. By inclining the studs a , and the recesses b , the sections A, and B, will be held in proper alignment at all times; as the inclined faces of the studs and recesses will abut one against the other. The sections A, and B, will not be thrown out of alignment as said sections are worn thin from use; but the same relative position as to alignment will be maintained throughout all the stages of wear and the various thicknesses of the sections.

Having fully described our invention, what we claim as new, and desire to secure by Letters Patent, is—

The combination of the sections A provided with the studs or projections having inclined faces upon one side thereof, the section B provided with inclined notches b formed in the edges of said section B, all of the sections having straight meeting edges and provided with the grooves c , substantially as and for the purpose specified.

In testimony that we claim the above we have hereunto subscribed our names in the presence of two witnesses.

LAROY S. PFOUTS.
LORENZO D. BALL.
